BOOSTER FOR LENS EDGE GRINDING MACHINES

Eli M. Long, Alamogordo, N. Mex., assignor to
Shuron Optical Company, Inc., Geneva, N. Y.,
a corporation of New York

Application October 6, 1950, Serial No. 188,710

8 Claims. (Cl. 51—101)

1

This invention relates to edge grinding machines for ophthalmic lenses and more particularly to a booster therefor.

In the manufacture of ophthalmic lenses, it is necessary to grind the edges of the lenses to the desired peripheral shape, for example, to fit a selected spectacle frame. This edging of the lens is usually accomplished by clamping the lens in a chuck which is slowly rotated while the edge of the lens is held against a rotating grinding wheel. A pattern, or sizer, of the same shape as required for the finished lens, is mounted usually coaxially with the lens to rotate with the chuck. A stop-device, or shoe, is adjustably fixed in relation to the grinding wheel so as to be contacted by the edge of the sizer to limit the travel of the chuck toward the grinding wheel as the edge of the lens is ground away. Since the lenses required by most ophthalmic mountings today are of irregular shape, some portions of the perimeter of the lens require more grinding, and hence longer contact with the grinding wheel, than others. This is due to the fact that the flatter portions of the periphery present longer arcs of contact with the grinding wheel than the more convex portions.

Attachments, called boosters, designed to decrease the grinding time in such machines in the past have been either of the intermittent or of the variable speed type. Attachments of the intermittent type provide means for stopping the rotation of the lens until the sizer comes into contact with its shoe, whereupon the lens is rotated just far enough to present a new, unground portion of the perimeter to the grinding wheel. With this start-stop type of device, the lens is ground down to substantially the shape required in one complete revolution of the lens. Attachments of the variable speed type do not attempt to grind down the edge of the lens to the required limit in one revolution of the lens, but provide means for speeding up the rotation of the lens whenever the sizer comes into contact with its shoe. The herein-described invention is of this slow-fast type, which is superior to the start-stop type because shorter arcs of contact between lens and grinding wheel are maintained. Devices of the variable speed type heretofore have usually been clutch arrangements with means for shifting from a low gear to a high gear ratio in the drive for rotating the lens. Such devices necessitate a temporary interruption of the transmission of rotary motion to the lens while the shift in gears is made.

The booster which is the subject of the present

2

invention, speeds up the rotation of the lens by means of an auxiliary motor operating upon one of the gears of a differential gear train which is normally prevented from rotating by reason of the construction of the gearing. This motor is energized by means of a micro-switch when the sizer comes into contact with its shoe, and is de-energized when an unfinished part of the edge of the lens comes into contact with the grinding wheel. A novel braking device on the motor insures the immediate stopping of the motor upon its being de-energized.

Such construction insures that rotary motion is continuously transmitted to the lens so that the edge of the lens will be continuously and smoothly ground away to the desired size.

One of the principal objects of the invention is to provide means whereby the time usually required for edging a lens is reduced.

Another object is to provide automatic means for increasing the speed of rotation of the lens while finished portions of the edge of the lens are adjacent the grinding wheel.

Another object is to provide positive drive means for rotating the lens and means for increasing the speed of rotation of the lens without interrupting the positive connection between the power source and the rotating lens.

A further object is to provide means for immediately decreasing the speed of rotation of the lens when an unfinished portion of the perimeter of the lens is presented to the grinding wheel.

A still further object is to provide an attachment which may be easily connected to an edging machine to increase its efficiency.

Other objects and advantages of the present invention will be apparent from the following description taken in conjunction with the accompanying drawings, in which:

Figure 1 is a side elevational view of a lens edging machine with the attachment connected thereto;

Figure 2 is a top plan thereof;

Figure 3 is an enlarged, fragmentary, side-elevational view of the sizer switch and adjacent parts of the attachment, with a portion of the switch housing broken away;

Figure 4 is a sectional view on the line 4—4 of Figure 3;

Figure 5 is a sectional view on the line 5—5 of Figure 6;

Figure 6 is an enlarged side-elevational view of the attachment and adjacent parts, partly in section on the line 6—6 of Figure 8, and with a

portion of the motor housing broken away to show the motor brake;

Figure 7 is a sectional view on the line 7—7 of Figure 8;

Figure 8 is a fragmentary top plan of the attachment, partly in section on the line 8—8 of Figure 6;

Figure 9 is a sectional view of the planetary gearing on the line 9—9 of Figure 6; and

Figure 10 is a side-elevational view of the 10 planetary gear support of Figure 9.

Referring more particularly to the drawings, an edging machine 10, as shown in Figures 1 and 2, which is more fully described in my United States Patent No. 1,272,474, comprises a grinding wheel 11 mounted on a shaft 12 which is supported in suitable bearings 13 secured to a base 14. Base 14 is adapted for mounting on a bench or stand and is in the form of a trough containing the lower portion of the wheel 11 and having side 20 flanges 15 and an upwardly and forwardly inclined guideway 16 at the front. On guideway 16 is adjustably secured a movable section 17 for receiving and supporting the sliding carriage 18. A shield 19 encloses the rear portion of the 25 wheel 11.

To one end of shaft 12 is secured a pulley 20 (Figure 2) connected to a motor, not shown, by which grinding wheel 11 may be rotated. To the other end of shaft 12 is secured a pulley 21 which drives pulley 22 by means of a belt 23. Pulley 22 is secured to a shaft 24 mounted transversely in the front portion of base 14 in suitable bearings and which operates a hydraulic mechanism, not shown, which reciprocates carriage 18 transversely of the machine. The extent of the reciprocatory motion of carriage 18 is adjustable by means of the screws 25.

Carriage 18 is provided at its opposite ends with upwardly and rearwardly extending arms 26, to the upper ends of which is pivotally secured the lens chuck frame 27, said frame being thus oscillatable toward and away from the grinding wheel. Secured to one end of frame 27 above its axis of movement is an extension 28 in which is journaled the lens chuck drive shaft 29 to which rotary motion is transmitted from the grinding wheel shaft 12 through pulleys 21 and 22 and shaft 24 as follows:

Shaft 24 projects from base 14 through a cylindrical boss 24' (Figures 7 and 8) and extends beyond pulley 22. Near this end of shaft 24 and exterior to pulley 22 is secured a worm 30 (Figure 6) which, by means of gearing hereinafter described, transmits rotary motion to the flexible shaft 31, the upper end of which is provided with a spiral gear 32 meshing with a similar spiral gear 33 on the shaft 29.

The upper end of flexible shaft 31 is journaled in a yoke 34 which is pivotally secured to an arm 26 by screw-stud 35. The yoke 34 is journaled on an eccentric portion of a rock shaft 36 having its ends journaled in a pair of forwardly projecting arms 37 (Figure 1) forming part of the extension 28 of the oscillating frame 27, the rock shaft 36 being provided with a radially extending handle 38 by which it may be rocked to shift the gear 32 into and out of mesh with the gear 33 for stopping and starting rotation of the lens independently of the grindstone. The outer end of shaft 29 is provided with a hand wheel 39 by which shaft 29 and the parts operated thereby may be independently rotated.

The lens chuck frame 27 best seen in Figure 2, comprises an upper portion 40 which houses a

transverse shaft, not shown, connected to rotate with the lens chuck drive shaft 29, side portions 41 and 42, and a lower lens chuck portion 43, comprising a pair of coaxial lens clamping members 44 and 45 arranged end to end and having their adjacent ends provided with suitable pads for receiving and retaining the lens 46 between them. The lens clamping members are operatively connected to rotate with separate coaxial rotary spindles 47 and 48. These spindles are journaled in suitable bearings in the lower portion 43 of the frame 27 some distance below and parallel with the axis of pivot of said frame and also parallel with the axis of the drive shaft 29, each spindle being connected by a similar train of gears, housed in portions 41 and 42, respectively, to the opposite ends of the transverse shaft housed in portion 43, so that each spindle is driven at the same rate.

Lens clamp 45 and its spindle 48 are retractable away from clamp 44 by means of lever 50 and mechanism, not shown, housed in portion 42 of the lens chuck frame, so that lenses may be easily and quickly clamped in the machine. Between lens clamp 44 and its spindle 47 is the pattern or sizer 51 secured to rotate therewith and easily removable therefrom by means of mechanism not shown. Spindles 47 and 48 thus operatively form a single work spindle.

A sizer shoe 52 (Figures 2 and 3) is secured to slide 18 adjacent the side of grinding wheel 11 by mechanism hereinafter described. It is adjustable, by means of the adjusting wheel 53, toward and away from the axis of rotation of the grinding wheel 11 and is located in the path of sizer 51 on the lens holding frame 27 as said frame is swung toward grinding wheel 11, acting as a stop to prevent grinding away more than the required amount at the end of the lens 46.

A hone 54 (Figure 2) for truing the grinding wheel is also carried by slide 18.

Mechanism to rock frame 27 with its attached lens 46 toward the grinding wheel 11 is provided in the form of lever 55 (Figures 1 and 2) pivoted at 56 to the shield 19. A forwardly and rearwardly extending guide 57 on lever 55 is provided with an adjustably mounted weight 58 thereon, the latter being held in its adjusted position by a set screw 59. Lever 55 is provided with a downwardly projecting arm 60 connected by a link 61 to frame 27 below its axis of swing.

The lens edge grinding machine 10 thus far described constitutes the setting of the present invention, rather than the invention itself, and is already known to the art through commercial edge grinders manufactured under said Long Patent 1,272,474. The foregoing description is therefore believed to be ample for the understanding of this invention, the features of which will now be described in greater detail.

The booster attachment which is the subject of the present invention is shown in Figures 1 and 2 and comprises an auxiliary motor 65, certain gears in a gear box 66, a sizer switch mechanism 67 and certain electrical wiring and an electrical junction box 68.

The gear box or casing 66 is best shown in Figures 7 and 8 mounted on shaft 24 outside of pulley 22 and has an arm 69 which extends around the other side of pulley 22 and clamps on boss 24' by means of clamping screw 70. The gear box 66 may be adjusted to the proper angle by the jack screw 71 which projects downward from arm 69 and rests on the side flange 15 of

the machine 10. A suitable bearing 72 (Figure 1) is provided for the end of shaft 24.

As best seen in Figures 6 and 8, a worm gear 13, mating with the worm 30 is mounted on, and secured to, a shaft 74 at right angles to shaft 24. Suitable supporting bearings 75 and 76 for shaft 24 are provided in gear box 66, and a spur gear 77 is formed integrally on shaft 74 as shown, or keyed thereto, within gear box 66.

On a parallel countershaft 78, shown as a stub shaft secured to casing 66 by a screw 79, is another spur gear 80 in constant mesh with the gear 77.

Another parallel shaft 81 is journalled in casing 66 at 82 and 83, and has a tubular planetary gear support member 84 rotatably mounted thereon. To the upper end of member 84 is keyed the spur gear 85 in constant mesh with gear 80. An arm 86 projects radially from the lower end of member 84 (Figures 9 and 10) and, joined thereto, is a yoke portion 87 on which is mounted a planetary gear shaft 88 parallel with shaft 81 and secured by set screw 89. On shaft 88, between the arms of yoke 87, are rotatably mounted the planetary gears 90 and 91 which are interlocked, as shown, to rotate together.

The lower planetary gear 91 is in constant mesh with a driven sun gear 92 keyed to shaft 81 below member 84. The upper planetary gear 90 is in constant mesh with another, or driver, sun gear 93 rotatably mounted on the tubular portion of member 84. Gears 93 and 90, and gears 92 and 91, respectively, have different numbers of teeth for reasons which will hereinafter appear. In the particular embodiment shown, gears 91 and 93 each have 17 teeth and gears 90 and 92 each have 18 teeth.

A large spur gear 95 is mounted coaxially on the driver gear 93 and is joined thereto by means of pins 94, and is in constant mesh with the gear 96. Gear 96 is keyed to the shaft 97 which is parallel to shafts 81, 78 and 74 and journalled in casing 66 at 98 and 99.

Keyed to shaft 81, about member 84, another spur gear 100 is mounted in constant mesh with the gear 101, which, in turn, is rotatably mounted on countershaft 78 above gear 80. Gear 101 is also in constant mesh with a gear 102 which is shown as coaxially mounted by means of an integral stub shaft 103 borne in a bored hole in the end of shaft 74. Gear 102 is formed with a suitable socket therein for operatively receiving the lower end of the flexible shaft 31, and is also journalled in casing 66 at 104. A dust cap 105 and oil seal 106 may be provided about the lower end of the shaft 31.

Casing 66 is preferably formed in two parts, as best shown in Figure 6, the upper part 110 being joined to the lower part 111 by screws 112. The interior may be filled with oil to a suitable level, a filler plug 113 being provided at the top and a drain plug 114 at the bottom.

The auxiliary electric motor 65 is secured to casing 66 by screws 115 and the armature shaft 116 thereof extends into the interior of the casing and is journalled therein at 117 and 118 so as to be parallel with shafts 97, 81, 78 and 74. Keyed to the motor shaft 116 is a worm 120 which is in constant mesh with the mating worm gear 121 on shaft 122. Shaft 122 extends across the casing 66 perpendicular to shaft 116, and is journalled at 123 and 124 in suitable manner. Worm gear 121 is keyed to shaft 122 as is the worm 125 thereon which is in constant mesh with the

mating worm gear 126 which is keyed to the reduced upper portion of shaft 97 above gear 96.

Motor 65 is provided with a fan 130 (Figures 5 and 6) which is secured to a metal brake disk 131 by screws 132. Disk 131 is secured to shaft 116 by a set screw 133 so as to provide end play in the shaft 116 on the order of .015 inch for reasons which will hereinafter become apparent.

To the main body of motor 65 which contains the usual field coils, is secured a metal ring 134 by screws 135. To the upper surface of ring 134 is cemented a leather brake ring 136 with any suitable adhesive, the upper surface of ring 134 and the lower surface of brake disk 131 being parallel and in planes normal to the axis of shaft 116.

Shaft 116 is provided with the usual armature, and a housing 137 with a suitable ventilating cover 138 is provided about the motor being spaced therefrom by longitudinally disposed fins 139 to provide ventilating passages for the fan 130.

The sizer switch 67, as shown in Figures 3 and 4, is supported by the screw 140 which is threaded into a portion of the reciprocating slide 18 at 141 and to which the adjusting wheel 53 is secured. The square lower portion of screw 140 has a projecting lug 142 which is guided in slot 143 (Figure 3) of the slide 18 and in which is seated one end of a coil spring 144, the other end of which is seated in a suitable pocket in slide 18. At 145 a yoked switch support bracket 146 is pivotally secured to the screw 140. The extent to which bracket 146 may pivot with respect to screw 140 is limited by means of set screws 147 and 148 which are threaded through screw 140 from opposite directions and contact bracket 146 and thus provide means for adjustably positioning the conventional microswitch 150 which is secured to bracket 146 by bolts 151. Also secured to bracket 146 by means of a bolt 152 is the conventional sizer shoe 52.

A switch operating arm 155 is also adjustably positioned on the reduced rounded lower end of screw 140 by means of the clamping bolt 156. A switch operating button 157 is located on arm 155 so as to contact the microswitch button 158 and a switch stop 159 is positioned adjacent a suitable portion of switch 150.

A dust cover or housing of aluminum or other light material is provided in two parts 160 and 161, bolted together at 162 and secured to arm 155 by bolts 163. Suitable openings for projecting portions of bracket 146 and screw 140 are provided between the portions 160 and 161 of the housing. An insulated cable 164 contains the lead wires connected to the terminals of microswitch 150 and which lead to appropriate terminals in the electrical junction box 68.

Junction box 68 (Figures 1 and 2) is clamped or bolted in any convenient manner to the side flange 15, as by bolts 165, to the rear of pulley 21. A conventional signal light 166 projects upward from the junction box 68 and is wired in conventional manner to light up when the sizer 51 is in contact with its shoe 52. The junction box 68 contains the necessary terminals and wiring and is provided with an intake cable 167 containing lead wires adapted to be connected to an electric power source. An insulated cable 168 contains lead wires from the appropriate terminals in motor 65 to those within the junction box.

In the operation of the attachment, it will be understood that an unedged lens 46 and an appropriate sizer 51 are placed in the machine 10

and clamped in place by operation of the lever 50. Weight 53 is adjusted to the proper position on the guide 57 and the lens holder frame 27 is swung down toward the revolving grinding wheel 11. The slide 18 reciprocates transversely carrying the lens across the face of the grinding wheel 11. The lens 46 is rotated as it rests against the face of the grinding wheel and its edge is ground away in the usual manner.

Rotation of the lens 46 is accomplished as follows: Pulley 21, being secured to the grinding wheel shaft 12, rotates shaft 24 by means of belt 23 and pulley 22. To shaft 24 is secured the worm 30, which being in mesh with the worm gear 73 of the attachment imparts rotary motion to shaft 74 to which it is secured. The gear 71, being joined to shaft 74, rotates therewith turning the spur gears 80 and 85, gears 77 and 85 being in constant mesh with gear 80. Gear 85 is keyed to the planetary gear support 84 which is therefore rotated about shaft 81 carrying with it the planetary gears 90 and 91. Gear 90 is in constant mesh with the sun gear 93, which is held stationary since it is keyed to the large gear 95 which is held stationary by reason of the series of worms and gears connecting the motor shaft 116 to the gear 96 as hereinafter more fully described.

Since the driver gear 93 is held stationary as the planetary gear 90 is rotated about it, gear 90 is forced to rotate on its shaft 88. Gear 91, being interlocked with gear 90, is forced to rotate at the same speed. Gears 93 and 90, and 92 and 91, respectively, having different numbers of teeth, the driven gear 92 is forced to rotate with respect to gear 93 and carries with it shaft 81.

Since gear 100 is keyed to shaft 81 and since gears 100 and 102 are both in constant mesh with gear 101, gear 102 is rotated, carrying with it the lower end of the flexible shaft 31. This rotary motion is transmitted through the upper half of the flexible shaft 31 and its attached spiral gear 32 to the mating gear 33 attached to shaft 29.

Shaft 29, in turn, drives the spindles 47 and 48 and the lens clamps 44 and 45 of the lens chuck through the gearing enclosed in the side portions 41 and 42 of the lens chuck frame 27 as hereinbefore described.

When a portion of the edge of lens 46 has been ground down to the required size, the sizer 51 contacts shoe 52. Shoe 52 is secured to the bracket 146 which carries the switch 150. As sizer 51 presses against shoe 52, bracket 146 is pivoted slightly on its pivot bolt at 145, thus forcing switch 150 and its button against button 157 on the switch operating arm 155. This pressure operates switch 150 causing the motor 65 to be energized.

Further motion of switch 150 and shoe 52 is prevented when switch 150 comes to rest against the stop 159 on the operating arm 155. Shoe 52 now becomes a positive stop and prevents sizer 51 and lens 46 from swinging toward the grinding wheel 11. Lens 46 would now be rotated slowly adjacent, but out of contact with, wheel 11 if it were not for the action of motor 65 which will now be described.

When the pressure of sizer 51 on shoe 52 operates the switch 150, the motor 65 is energized and shaft 116, with its attached worm 120, is caused to rotate. This rotation is transmitted through the worm gear 121, the shaft 122 and worm 125 to the worm gear 126. Gears 126 and 96 being keyed to shaft 97, the large spur gear

95, mating with gear 96, is caused to rotate. The driver sun gear 93 is secured to gear 95 and so rotates with it causing the meshing planetary gear 90 to rotate at a faster rate on its shaft 88. The planetary gear support 84 is still rotating as hereinbefore described and the rotation imparted by motor 65 is added to that imparted by the rotation of shaft 24. Gear 91 being in mesh with gear 92, this increased rotation is imparted through shaft 81, gears 100, 101 and 102 to the flexible shaft 31 and thence to the work spindle 47-48. It will be understood from the foregoing that there is no shifting of gears or interruption of the continuous and positively transmitted rotation of lens 46.

The increased rate of rotation of lens 46 is maintained until an unfinished portion of the edge of lens 46 is presented to the grinding wheel 11. As this unfinished portion comes into contact with the grinding wheel the lens chuck frame 27 is swung away from the grinding wheel and the sizer 51 is carried with it, removing the pressure on shoe 52. When the pressure on the sizer shoe is removed, it will be seen that the conventional switch spring of the microswitch 150 will operate the switch to terminate the flow of electricity to motor 65. This motor is prevented from coasting or overriding, with a consequent over-rotation of lens 46, by the novel brake built into the motor, which will now be described.

When power is supplied to motor 65 an inductive force is set up in the field coils which causes the armature and its shaft 116 to rotate. This same inductive force also results in a solenoid action familiar to those skilled in the art. The motor armature and shaft 116 are thus lifted up, the attached brake disk 131 is separated from the brake ring 136 and the motor 65 runs freely. As soon as the flow of electricity to the motor 65 is interrupted, however, shaft 116 with its attached armature drops of its own weight and the brake disk 131 falls against the brake ring 136, the friction of one against the other causing substantially immediate stopping of the rotation of shaft 116.

It will be understood, therefore, that when an unfinished portion of the edge of lens 46 contacts grinding wheel 11, sizer 51 is withdrawn from its shoe 52, switch 150 is turned off and the rotation of motor 65 immediately stops. Lens 46 now rotates slowly again, being turned by shaft 24 as hereinabove described. This slow rotation of lens 46 continues until another finished portion of the edge of the lens is presented to the grinding wheel when the motor 65 is again turned on and rapid rotation of lens 46 again takes place. This slow-fast rotation continues until the edging of the lens is completed.

While the actual speed of rotation of the lens comprises no part of the present invention, the approximate speed of rotation of some of the parts of the commercial embodiment of machine 10, with the attachment in use, are given herein with and the direction of rotation is indicated by arrows in the drawings for greater ease in understanding the above description. The single thread worm on shaft 24 normally operates at 200 R. P. M. and operates through the hereinabove described low speed gear train to drive the flexible shaft 31 at one R. P. M. Motor 65 operates at 1700 R. P. M. and, through the double thread worm 120, the four-thread worm 125, and the above described high speed gear train, drives flexible shaft 31 at 10 R. P. M. It will be ap-

parent that the construction of worms 120 and 125 makes their action non-reversible so that the large gear 95 is held stationary when motor 65 is stopped.

The lamp 166 may be wired into the electrical circuits in well-known manner to light up when sizer 51 is in contact with its shoe 52 and switch 150 is turned on. When the lamp is lit continuously, therefore, the operator knows that the edging of the lens is completed.

It will be understood by those familiar with the art that the hereinabove described attachment, comprising sizer switch 67, transmission 66 with the attached motor 65, junction box 68 and the attached wiring, may be easily added to the known edge grinding machine herein described. A flexible shaft 31 is supplied with the attachment which is shorter than that on the commercially known machine heretofore supplied and, on some models, a longer shaft 24 must be installed. It will be apparent that by disengaging the screw at 35, removing the sizer shoe adjusting wheel 53, and sizer shoe supporting mechanism, in well-known manner, and removing pulley 22 and the yoke supporting the lower end of flexible shaft 31 on the commercially known machine, that the hereinabove described attachment may be easily and quickly installed.

While there is herein described, and in the drawings shown, illustrative embodiments of the invention, it is to be understood that the invention is not limited thereto, but may comprehend other constructions, arrangement of parts, details and features without departing from the spirit of the invention. I desire to be limited, therefore, only by the scope of the appended claims.

I claim:

1. In a lens edge grinding machine, the combination with a frame, a rotatable grinding wheel journaled in said frame, rotatable means movably mounted on said frame for supporting a lens to be edged by said wheel, a sizer mounted on said supporting means for simultaneous rotation with the lens, means for moving said supporting means with the lens and sizer toward said wheel, and a sizer shoe mounted on said frame for engaging said sizer to limit said movement, of positive drive means for rotating said lens and sizer at slow speed, independent gearing means permanently geared to said positive drive means for increasing said speed of lens and sizer rotation when said independent means is driven, and means actuated by the engagement and disengagement of the sizer with the sizer shoe for driving and stopping said independent means without interrupting the positive drive of the lens and sizer.

2. In a lens edge grinding machine, the combination with a frame, a rotatable grinding wheel 60 journaled in said frame, rotatable means movably mounted on said frame for supporting a lens to be edged by said wheel, a sizer mounted on said supporting means for simultaneous rotation with the lens, means for moving said supporting means with the lens and sizer toward said wheel, and a sizer shoe mounted on said frame for engaging said sizer to limit said movement, of positive drive means for rotating said lens and sizer at slow speed, independent gearing means permanently geared through differential gearing to said positive drive means for increasing said speed of lens and sizer rotation when said independent means is driven, and means actuated by the engagement and dis-

engagement of the sizer with the sizer shoe for driving and stopping said independent means without interrupting the positive drive of the lens and sizer.

5 3. In a lens edge grinding machine, the combination with a frame, a rotatable grinding wheel journaled in said frame, rotatable means movably mounted on said frame for supporting a lens to be edged by said wheel, a sizer mounted on said supporting means for simultaneous rotation with the lens, means for moving said supporting means with the lens and sizer toward said wheel, and a sizer shoe mounted on said frame for engaging said sizer to limit said movement, of positive drive means including differential gear members for rotating said lens and sizer at slow speed, an auxiliary electric motor, gearing for driving one of said differential gear members by said motor at increased speed, and switch means actuated by the engagement and disengagement of the sizer with the sizer shoe for starting and stopping said auxiliary motor.

10 4. A lens edge grinding machine as claimed in claim 3, in which said auxiliary motor comprises a body provided with field coils and an armature mounted on a substantially vertically extending shaft, said shaft having attached thereto a brake disk, and said body having attached thereto a cooperating brake ring, whereby said motor is stopped substantially immediately upon switching off the electric current thereto.

15 5. An attachment for a lens edging machine having a frame, a rotatable grinding wheel journaled in said frame, rotatable means movably mounted on said frame for supporting a lens to be edged by said wheel, a sizer mounted on said supporting means for simultaneous rotation with the lens, means for moving said supporting means with the lens and sizer toward said wheel, and a sizer shoe mounted on said frame for engaging said sizer to limit said movement; said attachment comprising positive drive means including differential gear members for rotating said lens and sizer at slow speed, an auxiliary electric motor, gearing for driving one of said differential gear members by said motor at increased speed, and switch means actuated by the engagement and disengagement of the sizer with the sizer shoe for starting and stopping said auxiliary motor when said attachment is in position for use on the lens edging machine.

20 6. In a lens edge grinding machine, the combination with a frame, a rotatable grinding wheel journaled in said frame, a rotatable support for a lens to be edged movably mounted on said frame, a sizer mounted on said support for simultaneous rotation with the lens, means for moving said support with the lens and sizer toward said wheel, and a sizer shoe mounted on said frame for engaging said sizer to limit said movement, of positive drive means for rotating said lens and sizer, said drive means including differential planetary gears rotatable about a central sun drive gear and a central sun driven gear, means for selectively preventing the rotation of said sun drive gear and for rotating said sun drive gear, and means actuated by the engagement and disengagement of the sizer with the sizer shoe for starting and stopping the rotation of said sun drive gear.

25 7. In a lens edge grinding machine, the combination with a frame, a rotatable grinding wheel journaled in said frame, rotatable means movably mounted on said frame for supporting

11

a lens to be edged by said wheel, a sizer coaxially mounted on said supporting means for simultaneous rotation with the lens, means for moving said supporting means with the lens and sizer toward said wheel, and a sizer shoe mounted on said frame for engaging said sizer to limit said movement, of means for rotating said lens and sizer operably connecting said grinding wheel and said lens and sizer and including a joined pair of differential planetary gears meshing, respectively, with a sun drive gear and a sun driven gear, an auxiliary electric motor operably connected for non-reversible rotation of said sun drive gear, and switch means actuated by the engagement and disengagement of the 15 sizer with the sizer shoe for starting and stopping said motor.

8. A lens edge grinding machine as claimed in claim 7 wherein the auxiliary motor comprises a body having field coils and an armature having 20

12

a substantially vertically mounted shaft, said body having a brake ring secured thereto and said armature shaft having a cooperating brake disk secured thereto, whereby the energization of said field coils serves to lift said disk from said ring during operation of the motor and drops said disk on said ring to stop the motor when the electric current is shut off.
